VARIABLE VOLTAGE TRANSFORMER

John F. Hysler, Mount Vernon, N. Y., assignor to
 Ward Leonard Electric Company, a corporation
 of New York

Application December 13, 1944, Serial No. 567,992

6 Claims. (Cl. 171—119)

1

This invention relates to transformers of the adjustable voltage type and is particularly useful where close adjustment of the output voltage is required or when it is desirable to control this voltage over a wide range. The invention is applicable also to other variable contact devices.

The main object is to provide an improved form of apparatus which may be operated conveniently to secure any desired output voltage to a refined degree and over a wide range, such as from full voltage to one-half voltage or even less than one-half according to the particular design. In the disclosure described herein, the voltage range is from full voltage to about 70 per cent thereof. The close adjustment is obtained by providing exposed contact surfaces of a portion of the transformer winding itself for engagement by a slideable contact. These contact surfaces may be formed on successive turns of a portion of the winding for securing the most refined control, or may include two or more turns between contacts where such refined control is not required.

A further feature of the invention is to apply the adjustment of the turns to the winding of the transformer having the greater number of turns which would be to the primary winding in the case of the usual step-down transformer and to the secondary winding in the case of a step-up transformer. This secures the advantage of additional refinement of voltage adjustment and has the further advantage of conducting the smaller transformer current by the adjustable contact engagement.

Another object is to insure good and uniform contact of the engaging parts in all positions of control. Other objects are the securing of proper insulation of the operating parts and the provision of a structure which is dependable and durable under long continued use. Other objects and advantages will be understood from the following description and accompanying drawings.

Fig. 1 is a side view of a preferred embodiment of the invention; Fig. 2 is an end view thereof; Fig. 3 is a top plan view; Fig. 4 is a vertical section on the line 4—4 of Fig. 1; and Fig. 5 is a vertical section on the line 5—5 of Fig. 1.

The invention is shown applied to the usual shell type of transformer although it may be applied to any other form. The laminae of the core 10 are shown clamped together by through bolts

2

10a, one at each of the four corners. The transformer windings encircle the central leg 10b of the core. These windings are in three sections, a transformer of the step-down type being shown. 5 The primary winding is divided into two sections, an inner section 11 wound close to the central leg of the core and an outer primary section 11a wound on the outside of the intervening secondary winding 12, as shown in Fig. 2. This brings 10 the section 11a of the primary on the outside of the windings and thereby enables a slideable contact to engage successive turns of this outer section for securing the refined adjustment of the output voltage. Also, by this special relationship 15 of the different parts of the windings the leakage flux is reduced and permits the inner primary section 11 being wound close to the central leg of the core owing to its small size of wire compared with the comparatively large size of wire 20 of the secondary winding. Fig. 3 shows the leads 12a extending from the secondary winding to lugs 12b adapted for connection to the consumption circuit. A lead 10c of the primary winding is shown in Fig. 3 adapted for connection to the supply circuit and extends to the inner section 11 of the primary and from which section a lead 10d extends to the other section of the primary, thereby connecting these two sections in series 25 with each other.

30 As shown in Figs. 2 and 3, the outer section of the primary is shown in one continuous layer on the secondary winding. The upper left-hand portion of the outside section of the primary, as viewed in Fig. 2, is spaced from and supported by 35 a crosswise extending insulating strip 13 of insulating material and of rectangular form. It is held in place at each end by being bolted to a supporting bracket 14 of sheet metal. This bracket is shown formed in one piece having its 40 central portion passing close to the top of the middle leg of the core and within the transformer windings. At the sides of the windings the sheet metal is bent at right-angles to extend upwardly forming two triangular-shaped side portions as 45 shown in Fig. 2. The front part of each of these side portions is again bent at right-angles to form outwardly extending flanges 14a, as shown in Fig. 3; and the insulating support 13 is bolted to the upper part of these outwardly extending 50 flanges. These securing bolts also hold in place

a spacing plate 15 at each end of the insulating supporting strip 13 for holding the displaced portion of the outside winding in proper fixed position. As shown in Fig. 2, another insulating strip 16 extends crosswise within the outwardly spaced portion of the outer winding and is bolted in position at each end thereof to the flanges 14a of the supporting bracket and below the insulating strip 13. The strip 16 is of less thickness than the supporting strip 13 so that the turns of the winding which pass over the strip 13 are bent inwardly, as shown in Fig. 2, to engage the surface of the strip 16. Another strip 17 of insulating material extends crosswise in front of the strip 16 and is held in place at each of its ends by the same bolts which secure the strip 16 to the bracket 14. The strip 17 serves to clamp the turns of the outside winding firmly against the strip 16 and imposes a certain amount of tension on the turns where they pass over the strip 13. This insures that the outwardly spaced portions of the turns are held firmly and permanently in fixed position. After the winding is completed and properly supported as already described, the insulation on that portion of the spaced turns which pass over the front of the insulating strip 13 is removed by grinding off the insulation in order to expose the metal conductor of each turn over a straight path along the front of the conductors. This enables a slideable contact 18 to successively engage the conductor of each turn of the outer section of the winding as it is moved crosswise along the path of the exposed contacts from one end turn of the winding to the other end turn.

The controlling apparatus is supported by a pair of sheet metal brackets located on the top of and extending along the sides of the transformer core. These brackets are angular and each have an upwardly extending portion 19 at the outer portion of the core and an inwardly extending portion 19a and are secured in fixed position by the clamping bolts 10a of the transformer core. The front end portions of the brackets 19 are cut away as indicated in Fig. 2 and thereby provide clearance space for the passage of the ends of a square metal conducting rod 20. The other ends 20a of this rod are of reduced size to pass through and be supported by blocks 21 of insulating material which are secured on the outer faces of the brackets 19 by the screws 21a. The insulated rod 20 has one of its ends 20a projecting beyond its support 21 and is threaded to receive nuts 20d for connecting thereto the lead wire 10d from the source, the other lead 10c from the source to the primary winding having already been described.

A screw shaft 22 is supported at its ends in bearings provided by the supporting metal plates 23. These plates are of general horseshoe form with the arms bridging and spaced from the rod 20, as shown in Fig. 2, and secured at their inner ends to the brackets 19 by the screws 21a. One end of the drive shaft 22 is provided with a knob 22a, although any other suitable means may be provided for turning this shaft or rod.

Mounted on the screw shaft 22 and adapted to travel thereon is a block 24 of insulating material. This block has a central circular opening, as shown in Fig. 4, through which the drive rod or shaft 22 freely passes. An opening is formed in the central front portion of the block affording space for a drive pin 25 which has a small projection at its inner end engaging the spiral groove of the threaded drive rod. The pin 25 is fixed at its front end to a central end portion of a yield-

able metal plate or leaf spring 26. The two side extensions of this spring are riveted, as indicated in Fig. 4, to the block 24. It is apparent that when the drive rod is turned, the engagement of the drive pin therewith will cause the block 24 to move along the drive rod in one direction or the other according to the direction in which the drive rod is turned, the leaf spring serving to hold the drive pin in engagement with the drive rod. It is desirable that this traveling block should not move beyond desirable limiting positions at each end of its movement, and to insure this limitation of movement, the outer thread portion of the drive rod is cut away at the desired limiting positions. These cut down portions of the thread are shown at 22a and 22b in Fig. 3 and provide beveled surfaces which extend circumferentially from the inner diameter of the thread to the outer diameter. Thus when the block 24 reaches either of these positions, the drive pin instead of continuing to follow the groove of the drive shaft will ride up on the beveled portion 22b to the outer surface of the drive shaft at that location and no matter how much the drive shaft is turned, the drive pin will continue to ride up on this beveled portion during each revolution of the drive rod and thereby avoid further travel of the rod beyond this limiting position. However, when the shaft is turned in the opposite direction, the drive pin will then follow the groove of the drive shaft and move away from its extreme position. Obviously these beveled surfaces 22a and 22b may be formed at any portions of the drive rod for limiting the travel as may be desired at the two end limits. The leaf spring 26 permits the drive pin to move outwardly and ride up the beveled surface to the outer portion of the drive rod at each limiting position and then forces the drive pin into engagement with the groove of the drive rod when it is turned in the opposite direction.

On the inner face of the block 24 is a rectangular projection 24a extending longitudinally in the direction of the drive rod. Another block 27 of metal, such as brass, is secured to the inner face of the insulating block 24. The block 27 is shaped to embrace the conducting rod 20 and to also embrace the projection 24a of the insulating block, as shown in Fig. 4. The block 24 is provided at its upper and lower central portions with holes for permitting the insertion of screws 28, 28a and with openings of reduced diameter for the passage of the shanks of these screws to engage the block 27 and hold the same in fixed position to the block 24. Thus the block 27 is carried with the block 24 in its traveling movement and sufficient clearance is provided around the square conducting rod 20 to permit free movement along the same.

The upper central portion of the block 27 is provided with a cylindrical hole extending from the inner face to near the front portion; and in this opening is a metal cylinder or plunger 29 having a slidably fit with the block 27 and serving as the contact holder. A spring 30 is located within the central opening of the holder 29 and impinges against the block 27, thereby biasing the holder 29 outwardly from the block. The contact 18 previously described, is fixed to the projecting end of the holder 29 and engages the exposed contact surfaces of the winding along the path already referred to. A copper strip 31 is connected from the contact 18 to the block 27, being secured to the latter by the screw bolt 28a. It is apparent that a good electrical connection

is obtained to the conducting rod 20 and to the lead 10d from the contact 18 by its connection to the metal block 27 through the lead 31 and through the contact holder and by the slidable engagement of the block 27 with the conducting rod 20 in any adjusted position of the device.

The conductive engagement of the block 27 with the rod 20 is increased by the additional means shown particularly in Fig. 5. This is accomplished by a cylindrical pin 32 slidably movable through an opening in the block 27 opposite the top of the rod 20. This pin is positioned in an upper side portion of the block 27 as indicated by dotted lines in Fig. 1. A yieldable strip 33 of sheet metal forming a leaf spring extends over the top of the block 27 and is secured thereto at one end by the screws 34, the free end of the leaf spring engaging the top of the pin 32. The pin is centered in position in the spring by a small projection at the top thereof extending through a small hole in the leaf spring. It is evident that this device serves to draw the block 27 firmly against the underside of the conducting rod 20 for insuring good electrical engagement between the block 27 and the rod 20.

It is apparent that when the knob 22a of the drive shaft is turned, more or less of the turns of the outside section 11a of the primary winding will be included in the supply circuit for obtaining a refined adjustment of the output transformer voltage. In one limiting position of the traveling block 24, all of the turns of the section 11a of the primary will be included in the supply circuit whereas in the other limiting position of the block none of the turns of the primary section 11a will be included in the supply circuit. This improvement thereby not only obtains a refined adjustment of the output voltage but secures a wide range of control as determined by the number of turns in the different parts of the transformer windings. In some cases the winding having the variable number of turns may be completely outside the other winding of the transformer instead of being divided in sections as in the particular embodiment herein described; and in such a case the variable portions of the outside winding will form the outer layer. The invention may be applied to either the primary or the secondary transformer windings or sections thereof and certain features of the invention may be applied to a transformer having a single winding and to its outer layer and to inductive or reactive windings of various types. Also, certain features of the invention may be applied to various forms of variable contact devices.

Although a particular embodiment of the invention has been described, it will be understood that various modifications may be made for adaptation to particular requirements without departing from the scope of the invention.

I claim:

1. An inductive device comprising a core, a winding wound thereon having a plurality of layers, a support extending crosswise under portions of the outside layer of the winding for supporting such portions of the winding at a displaced position with reference to the remainder of the winding, said displaced portions having the insulation removed therefrom to form a contact path along adjoining turns, and a slidable contact movable along said path for successively engaging said adjoining turns.

2. An inductive device comprising a core, a winding wound thereon having a plurality of

layers, a support extending crosswise under portions of the outside layer of the winding for supporting such portions of the winding at a displaced position with reference to the remainder of the winding, a second support extending crosswise over said portions of the winding at one side of said first named support for holding the portions firmly against said first named support, said displaced portions having the insulation removed therefrom to form a contact path along adjoining turns, and a slidable contact movable along said path for successively engaging said adjoining turns.

3. An inductive device comprising a core, a winding wound thereon, said winding having exposed contact surfaces of certain of its turns positioned along a straight path, a contact movable along said path for successively engaging said contact surfaces, supporting means carried by said core, a screw shaft parallel to said path and journaled in said supporting means, a traveling block on said shaft for actuating said contact along said path, and a yieldable pin carried by said block engaging the groove of said shaft, said shaft having a beveled surface extending from the groove of said shaft to the outer portion of said shaft for limiting the movement of said block in one direction by causing said pin to pass out of said groove over said beveled surface.

4. An inductive device comprising a core, a winding wound thereon, said winding having exposed contact surfaces of certain of its turns positioned along a straight path, a conducting metal rod extending in a direction parallel to said path, a metal block slidable on and embracing said rod, a contact carried by said metal block, a spring within said block for biasing said contact outwardly therefrom for successively engaging said contact surfaces along said path upon movement of said block along said rod, a spring-pressed pin carried by said block and engaging said rod for exerting pressure of said block against said rod for insuring good electrical engagement between said block and rod, and means for actuating said block along said rod.

5. A variable contact device comprising a series of exposed contacts along a straight path, a conducting metal rod positioned parallel to said path, a metal block movable along and embracing said rod and in electrical contact therewith, a contact carried by said block electrically connected therewith, a spring within said block for biasing said contact outwardly therefrom for successively engaging said contacts upon movement of said block along said rod, a spring-pressed pin carried by said block and engaging said rod for pressing said block against said rod for insuring good electrical engagement between said block and rod, and means for actuating said block along said rod.

6. An inductive device comprising a core, a winding wound thereon, said winding having exposed contact surfaces of certain of its turns positioned along a straight path, supporting means carried by said core, a conducting metal rod extending in a direction parallel to said path and supported by and insulated from said supporting means, a metal block slidable on said rod, a contact carried by said metal block and biased outwardly therefrom for successively engaging said contact surfaces along said path upon movement of said block along said rod, a screw shaft parallel to said rod and journaled in said supporting means, a traveling block of insulating material

on said shaft secured to said metal block, and a yieldable pin carried by said insulating block engaging a groove of said shaft, said shaft having a beveled surface extending from the groove of said shaft to the outer portion of said shaft for limiting the movement of said block in one direction by causing said pin to pass out of said groove over said beveled surface.
